UNITED STATES PATENT OFFICE.

RANSOM Y. BOVEE, OF CHICAGO, ILLINOIS, ASSIGNOR TO B. A. FRANKLIN, TRUSTEE.

SCREW-CUTTER.

1,151,857.

Specification of Letters Patent. Patented Aug. 31, 1915.

Application filed August 20, 1913. Serial No. 785,735.

To all whom it may concern:

Be it known that I, RANSOM Y. BOVEE, a citizen of the United States, residing at Chicago, in the county of Cook and State of Illinois, have invented certain new and useful Improvements in Screw-Cutters, of which the following is a specification.

This invention relates to screw cutters and its principal object resides in the provision 10 of a tool of simple construction which by adjustment of its parts may be readily adapted for cutting internal and external screw threads of varying pitch and diameter.

15 An embodiment of my invention has been illustrated in the accompanying drawings in the various views of which like parts are similarly designated and in which,

Figure 1, represents a plan view of my 20 improved screw cutter, Fig. 2, an edge view of the same looking in the direction of the arrow A, Fig. 1, Fig. 3, a longitudinal section along the line 3—3, Fig. 2 looking in the direction of the arrow drawn across said 25 line, and Fig. 4, a section taken along the line 4—4, Fig. 1 drawn to an enlarged scale.

Referring to the drawings by numerical 30 reference characters, 2 designates a double-handled die stock which is transversely divided into two axially aligned, complementary halves.

The parts 3 and 4 of the stock are movably connected at their adjacent ends by 35 means of a hinge 5 which projects outwardly from an edge of the tool, and they are adjustably maintained in their closed, operative position by means of a latch-bolt 6 applied at the opposite edge of the same.

The bolt which is pivotally secured at one 40 of its ends in a recess of the member 3 of the stock, normally projects through a longitudinally cut channel 7 in the other member, and its threaded extremity is provided with a nut 8 which by engagement with a 45 shoulder 9 formed at the end of the channel, may be used to draw the two parts of the stock together to any desired distance between their adjacent ends.

The body-portions of the two parts of 50 the stock are each provided with a cylindrical chamber 10 which is open at one side and closed at its opposite side, and the handles 12 of the stock which extend oppositely from the respective body portions of its halves, 55 are hollow and provided at their ends with hinged, spring-held lids 13, for the storage

of a number of taps of different sizes as indicated at 14 in Fig. 3.

The hollows of the handles are separated from the chambers 10 by means of partitions 60 15, and registering ports 16 formed in the adjacent ends of the stock parts in a plane of the longitudinal axis of the tool, serve to admit a piece placed between the said parts, to die-members placed inside the 65 chambers as will hereinafter be more fully described.

The die-members above referred to consist of cylindrical blocks 17 of hardened steel 70 which are proportioned to occupy the chambers in the stock. They are each formed of an annular rim and an internal web which has a central opening to receive the pivot bolt by means of which the member is rotatably mounted in the respective chamber 75 of the stock part.

Each of the two die members has in the peripheral surface of its rim, threaded 80 grooves 19 of different diameters which in coöperation with corresponding grooves in the other member are adapted for cutting external screw threads on a piece inserted 85 between the parts of the die stock through an opening formed by registering notches 18 cut in their adjacent ends in the closed sides of their respective chambers.

In addition to the above mentioned threaded grooves, the die members have in their peripheral surfaces, angular grooves 90 20 which by proper adjustment of the members may be combined to provide sockets for the reception of the squared end of the taps 14 when inserted between the hinged parts of the stock.

The chambers 10 of the stock parts are 95 provided internally, at their closed sides, with concentric bosses 21 which are formed to fit inside the annular rims of the die-members to determine the proper central position of the latter in the chambers they 100 occupy.

The bolts 22 by means of which the die members are rotatably mounted in their respective chambers are at the ends of their stems screwed into central openings in the 105 side walls of the chambers and their transversely nicked heads 24 are formed to fit loosely within the portions of the die rims opposite to those occupied by the bosses 21.

The webs of the die members have concentric series of substantially equidistant apertures 23 which are arranged respec-

tively in the radii passing through the peripheral grooves of the members, and which are adapted to receive the ends of locking pins 25 screwed in threaded openings 5 formed in the closed side of the stock members in the plane of the longitudinal axis of the tool.

When by adjustment of the two rotary die members, corresponding peripheral 10 grooves thereof are brought into register in the plane above mentioned, to receive a piece inserted between the stock parts through the opening formed by the notches 18 in the closed side of their chambers, the 15 respective apertures in the webs of the said members are axially in alinement with the locking pins which by entering the same rigidly secure the members in their adjusted positions.

20 From the foregoing description the operation of my improved tool may be readily understood.

By withdrawing the pivot screws 22 sufficiently far to permit the die members to 25 turn free from the ends of the locking pins, the said members may be readily adjusted to bring any pair of complementary grooves in their peripheries in register in the plane of the longitudinal axis of the stock, for the 30 purpose of cutting external threads of any desired pitch or for holding taps of any gage, within the range of the tool.

By adjustment of the nut 8 on the latch bolt the space between the two members of 35 the stock may be varied to regulate the diameter of the incision made by the threaded die grooves or to clamp a tap securely in position, and in this connection I wish it understood that by graduating the bolt as 40 shown at 26 in Fig. 3, the distance between the two die-members may be measured to determine whether the thread cut by their coöperative action is oversize, standard or undersize.

45 Inasmuch as the die members are reversible in their respective chambers, a finished thread can be cut down to a flat surface and by virtue of the projecting position of the hinge 5, the members of the stock may be folded together to permit of placing the tool in a comparatively small space.

By reason of the hinged connection of the stock member the dies may be closed around a piece to be threaded at any desired point 55 thereof and the use of a guide or follower to start the thread at the proper angle is thus rendered unnecessary, while a thread can be rechased at any point without having to run the tool down the entire thread of the 60 piece in which the thread is formed.

It is obvious that by providing extra sets of dies, the range of the tool may be in-

definitely increased to cut external or internal threads of any desired pitch or diameter in pieces of different size, construction or material.

Having thus described my invention what I claim and desire to secure by Letters-Patent is:

1. A screw-cutter comprising a die-stock 70 composed of two parts connected by a hinge and having cylindrical chambers open at one of their sides and provided with ports which register when said parts are in their closed position, the said parts having bosses 75 extending concentrically in said chambers from their closed sides, die members disposed in said chambers to coöperatively engage a piece placed between said parts, through said ports, and each composed of 80 an annular rim provided with a series of peripheral grooves and an internal web having a corresponding concentric series of apertures, the bosses on the said parts being adapted to occupy the interior of the respective members at one side of their webs, pivot bolts screwed into the closed sides of 85 said chambers to rotatably secure the members within the same, and provided with heads adapted to occupy the interior of the 90 said members at the opposite sides of their webs, and lock pins secured in the closed sides of the chambers to enter said apertures for locking the members in their adjusted positions on the respective stock-parts.

2. A screw cutter comprising a die stock composed of two parts connected by a hinge and having cylindrical chambers open at one of their sides and provided with ports 100 which register when said parts are in their closed position, the said parts having bosses extending concentrically in said chambers from their closed sides, hollow, peripherally grooved die members disposed in said chambers to coöperatively engage a piece placed 105 between said parts, through said ports, the bosses on the said parts being adapted to occupy the interior of the respective members at one of their sides, pivot-bolts screwed into 110 the closed sides of said chambers to rotatably secure the members within the same and provided with heads adapted to occupy the interior of the members at the opposite sides of the same, and means for securing the 115 members in a plurality of determinate positions on the respective stock-parts.

In testimony whereof I have affixed my signature in presence of two witnesses.

RANSOM Y. BOVEE.
